(57) **CLAIM**

The ornamental design for a internet video camera, as shown and described.

DESCRIPTION

FIG. 1 is front elevational view thereof;
FIG. 2 is a rear elevational view thereof;
FIG. 3 is a right side view thereof;
FIG. 4 is a left side view thereof;
FIG. 5 is a top view thereof;
FIG. 6 is a bottom view thereof;
FIG. 7 is a front perspective view thereof; and
FIG. 8 is a rear perspective view of the design in a first configuration position; and
FIG. 9 is front elevational view thereof;
FIG. 10 is a rear elevational view thereof;
FIG. 11 is a right side view thereof;
FIG. 12 is a left side view thereof;
FIG. 13 is a top view thereof;
FIG. 14 is a bottom view thereof;
FIG. 15 is a front perspective view thereof; and,
FIG. 16 is a rear perspective view thereof.

The claim does not cover those features that appear in broken lines in the drawings, including any text that appears in the drawings.

1 Claim, 2 Drawing Sheets
